TELESCOPE MOUNT FOR FIREARMS

Frederick L. Humeston, New Haven, Conn., assignor, by mesne assignments, to Western Cartridge Company, a corporation of Delaware

Application February 24, 1937, Serial No. 127,389

7 Claims. (Cl. 33—50)

This invention relates to telescope mounts, and more particularly to mounts for supporting telescope sights upon firearms.

One of the objects of the present invention is to provide a simple, reliable and low-cost mount for attaching telescopes to firearms.

Another object is to provide a superior mount whereby telescopes may be conveniently and securely attached to firearms with capacity for adjustment, without, however, permitting any objectionable degree of slackness.

A further object is to provide a superior telescope mount of the type referred to which may be secured to and detached from the firearm structure with a maximum degree of convenience.

With the above and other objects in view, as will appear to those skilled in the art from the present disclosure, this invention includes all features in the said disclosure which are novel over the prior art and which are not claimed by me in a separate application.

In the accompanying drawing, in which certain modes of carrying out the present invention are shown for illustrative purposes:

25 Fig. 1 is a view in side elevation of one form which a telescope mount may assume in accordance with the present invention, and showing the said mount associated with a firearm-barrel and telescope-tube;

30 Fig. 2 is a top or plan view thereof;

Fig. 3 is a transverse sectional view taken on the line 3—3 of Fig. 1;

Fig. 4 is a similar view taken on the line 4—4 of Fig. 1; and

35 Fig. 5 is a perspective view of the clasp-member, detached.

The particular telescope mount herein chosen for the purpose of illustrating the present invention includes a sheet- or plate-metal clasp-member, generally designated by the reference character 10, and having a pair of oppositely-curved base-clasping arms 11 and 12, integrally united with each other at their upper ends, and also integrally united by means of a tie-web 13 with a 45 pair of oppositely-located tube-clasping arms 14 and 15.

The two complementary base-clasping arms 11 and 12 are each of substantially semicircular form in cross-section for encircling the top-portion and 50 the side-portions of a telescope-tube 35 in spaced relation thereto. At their lower portions the said arms 11 and 12 are extended into substantial parallelism, providing coupling-portions 16 and 17 respectively. The extreme lower ends 16 and 17 of the arms are both bent inwardly to respectively

provide opposed clasping-fingers 18 and 19 which are spaced apart and extend downwardly and inwardly in converging direction. The inner face of the clasping-finger 18 engages a similarly-sloped portion 20 of a base or support 21, and in a similar manner, the inner face of the clasping-finger 19 engages a portion 22 of the base 21, which portion is sloped to conform to the said finger. The base or support 21 is, in the particular instance shown, secured by a suitable number 5 of screws, such as 23, to a barrel 24 or other suitable portion of the firearm structure.

The downwardly-extending coupling portion 16 of the base-clasping arm 11 is provided with a threaded bore 25 receiving the threaded end of a 15 clamping screw 26, which also extends freely through a perforation 27 in the opposite coupling portion 17 of the base-clasping arm 12, adjacent which the said screw is formed with a knurled and kerfed head 28, the inner face of which latter 20 bears against the outer face of the portion 17, just referred to.

The clamping-screw 26, just above described, is preferably so positioned that its knurled head 28 is located below the encircling clasping-arm 25 12 and the said clamping-screw 26 extends transversely below the telescope-tube 35. A convenient and desirable substantially-symmetrical structural arrangement is thus obtained. In this position the clamping-screw 26 engages with the 30 upper surface of the base 21, and hence serves to stabilize the clasping-member both against bodily movement toward the barrel 24 and against tilting movement with respect to the block 21. It will be noted by reference to Fig. 3 in particular that the inner surfaces of the clasping-fingers 18 and 19, together with the transverse clamping-screw 26, outline (when viewed from the front, rear or in transverse section) what constitutes in effect a dovetailed groove receiving the dovetailed rib- 40 like upper portion of the base or support 21.

Returning now to the tube-clasping arms 14 and 15, it will be noted by reference to Figs. 4 and 5 in particular that the lower end of each depends from an encircling portion thereof and is bent into parallelism with the similar end of the other arm, providing coupling-portions 29 and 30 respectively. The coupling portion 30 of the tube-clasping arm 15 is provided with a threaded bore 31 receiving the threaded outer end of a 50 clamping-screw 32 which extends freely through a passage 33 in the coupling portion 29 of the tube-clasping arm 14. The inner face of the slotted head 34 of the clamping-screw 32 bears 55

against the outer face of the portion 29 of the tube-clasping arm 14, as shown in Fig. 4.

Preferably, as is particularly well shown in Fig. 4, the clamping-screw 32 is similarly positioned 5 below the encircling portion of the clasp-member. It is arranged at the rear of the said clamping-screw 26 and extends transversely of and below the said telescope-tube 35.

The base-clasping arms 11 and 12 of the clasp-member 10 are laterally curved, as shown, on an 10 arc substantially concentric with a telescope-tube 35, but their curvature is of such radius as to leave the said tube substantially free of direct restraint thereby. The tube-clasping arms 14 15 and 15 are also laterally curved on an arc concentric with the tube 35, but are proportioned to firmly clasp the exterior surface of the latter substantially throughout their entire length.

When the clasp-member 10 is in place upon the 20 firearm, so that its base-clasping fingers 18 and 19 are firmly clasped upon the portions 20 and 22 of the block 21 by means of the clamping-screw 26, the clasp-member will assume its normal rigid position with respect to the firearm. When 25 now the complementary tube-clasping arms 14 and 15 are firmly engaged with the periphery of the telescope-tube 35, by means of the clamping-screw 32, the said tube will be firmly supported by the clasp-member, but owing to the flexibility 30 of the tie-web 13, the said tube may be flexed both laterally and vertically with respect to the clasping-arms 11 and 12 and the supporting-structure, as indicated by broken lines A in Figs. 1 and 2, so as to permit the said telescope-tube to be initially 35 trued and properly adjusted by any suitable means to compensate for changes in range and wind velocity, or any other purpose. Furthermore, by loosening the clamping-screw 32, the tube-clasping arms 14 and 15 of the clasp-member may be 40 sufficiently freed from the tube 35 to permit the latter to be adjusted along its own axis.

Should it be desired to remove the clasp-member from the base or support, such, for instance, as the block-like member 21, this may be effected by loosening the clamping-screw 26 to 45 permit the support-clasping arms 11 and 12 to spring laterally away from the support 21.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalence range of the appended claims are intended to be embraced therein.

I claim:

1. A telescope mount for firearms folded up from sheet-metal and comprising: a clasp-member having two complementary support-clasping arms comprising an encircling-portion, and spaced substantially vertically-depending coupling-portions positioned directly opposite to each other laterally of the mount and each provided 5 with a clasping-finger constructed and arranged to engage with a sight-support of a firearm; a first clamping-member extending between the two said vertically-depending coupling-portions and serving to engage the clasping-fingers thereof 10 with a sight-support of a firearm structure; a pair of tube-clasping arms also carried by the said clasp-member and comprising an encircling-portion to engage and hold a telescope tube; and spaced substantially vertically-depending coupling-portions; and a second clamping-member 15 extending between the two said vertically-depending coupling-portions and serving to engage the tube-clasping arms with the said support-clasping arms; and a longitudinally-extending flexible web interconnecting the said tube-clasping arms with the said support-clasping arms.

engaging the said tube-clasping arms with a telescope and positioned immediately adjacent the said first clamping-member.

2. A telescope mount for firearms folded up from sheet-metal and comprising: a clasp-member having two complementary support-clasping arms comprising an encircling-portion, and spaced substantially vertically-depending coupling-portions positioned directly opposite to each other laterally of the mount and each provided 5 with a clasping-finger constructed and arranged to engage with a sight-support of a firearm; a first clamping-member extending between the two said vertically-depending coupling-portions and serving to engage the clasping-fingers thereof 10 with a sight-support of a firearm structure; a pair of tube-clasping arms comprising an encircling-portion to engage and hold a telescope tube; and spaced substantially vertically-depending coupling-portions; a second clamping-member 15 extending between the two said vertically-depending coupling-portions and serving to engage the tube-clasping arms with the said support-clasping arms; and a longitudinally-extending flexible web interconnecting the said tube-clasping arms with the said support-clasping arms.

3. A telescope mount for firearms folded up from sheet-metal and comprising: a clasp-member having two complementary support-clasping arms comprising an encircling-portion, and spaced substantially vertically-depending coupling-portions positioned directly opposite to each other laterally of the mount and each provided 30 with an inturned support-clasping finger converging toward the similar support-clasping finger of the other clasping-arm; a first clamping-member extending between the two said vertically-depending coupling-portions and serving to engage the support-clasping fingers thereof 35 with a sight-support of a firearm structure; a pair of tube-clasping arms also carried by the said clasp-member and comprising an encircling-portion to engage and hold a telescope tube and spaced substantially vertically-depending coupling-portions; a second clamping-member 40 engaging the said tube-clasping arms with a telescope and positioned immediately adjacent the said first clamping-member; and a flexible web interconnecting the said support-clasping arms and the said tube-clasping arms and located substantially diametrically opposite to both of the said clamping-members.

4. A telescope mount for firearms comprising: a support-engaging portion constructed and arranged to be engaged with a sight-support of a firearm and clear a telescope tube; tube-holding means constructed and arranged to engage and hold a telescope tube; and flexible means formed integral with and flexibly interconnecting the said support-engaging portion and the said tube-holding means, the said flexible interconnecting means extending longitudinally and radially between the said support-engaging portion and the said tube-holding means, whereby the tube-holding means is displaced longitudinally with respect to the support-engaging portion, and is arranged to directly engage and embrace a telescope tube and the support-engaging portion is arranged in spaced relation to the telescope tube.

5. A telescope mount for firearms comprising: 70 a clasp-member having two oppositely-located complementary support-clasping arms and two oppositely-located complementary tube-clasping arms longitudinally displaced with respect to the said support-clasping arms and comprising an 75

encircling-portion directly engaging and embracing the periphery of a telescope tube; and flexible means interconnecting the two support-clasping arms with the upper encircling-portion of two 5 said tube-clasping arms, the said tube-clasping arms thereby having capacity for movement to permit the swinging of a telescope tube with respect to the said support-clasping arms.

6. A telescope mount for firearms comprising: 10 a clasp-member having two complemental support-clasping arms comprising spaced substantially vertically-depending coupling-portions positioned directly opposite to each other laterally of the mount and two complemental tube-clasping arms comprising spaced vertically-depending coupling-portions and positioned directly opposite to each other laterally of the mount; and flexible means interconnecting the two support-clasping arms with the two said tube-clasping 15 arms, the said support-clasping arms being outwardly bowed sufficiently to clear a telescope tube held by the said tube-clasping arms, the said tube-clasping arms thereby having capacity for 20

movement to permit the swinging of a telescope-tube with respect to the said support-clasping arms.

7. A telescope mount for firearms comprising: 5 a clasp-member having two complemental support-clasping arms comprising spaced substantially vertically-depending coupling-portions positioned directly opposite to each other laterally of the mount and two complemental tube-clasping arms comprising spaced vertically-depending 10 coupling-portions and positioned directly opposite to each other laterally of the mount; longitudinally-extending flexible means interconnecting the said support-clasping arms with the said tube-clasping arms; a first clamping-screw extending between the coupling-portions of the two 15 said support-clasping arms at a point substantially diametrically opposite the said flexible means; and a second clamping-screw extending between the coupling-portions of the two said 20 tube-clasping arms and located immediately adjacent the said first clamping-screw.

FREDERICK L. HUMESTON.
